UNITED STATES PATENT OFFICE.

LOUIS JUDELSON, OF NEW YORK, N. Y.

LAUNDRY MACHINERY.

1,072,617.

Specification of Letters Patent. Patented Sept. 9, 1913.

Application filed May 22, 1912. Serial No. 698,951.

To all whom it may concern:

Be it known that I, LOUIS JUDELSON, a citizen of the United States of America, residing at New York city, in the county and State of New York, have invented certain new and useful Improvements in Laundry Machinery, of which the following is a specification.

My invention relates to laundry machinery, and more particularly to a type of heat drying apparatus for clothes.

The main object of the invention is to provide an apparatus of this character wherein articles of wearing apparel will be subjected while in a cabinet, to the action of dry, heated air, for sufficient time to remove the moisture therefrom, said articles being delivered mechanically to said drying chamber and mechanically removed therefrom in a manner to permit the handling of the wet and dried articles exteriorly of the cabinet.

A further object is to provide an apparatus of this character wherein a circulation of air will be maintained about the articles being dried at all times while they are within the cabinet, thus, through the elimination of moist air, preserving conditions whereby the clothes will be properly dried within the minimum time.

A still further object is to provide an apparatus of this character wherein the air delivered into and withdrawn from the cabinet will be so diffused as to insure uniform conditions throughout the cabinet.

A still further object is to provide an apparatus of this character containing a normally closed cabinet within which a conveying mechanism is installed, the feed and delivery ends of said conveying mechanism being exposed exteriorly of the cabinet, automatically acting doors being provided whereby the articles of clothing may be introduced to the cabinet and removed therefrom without permitting the escape of any material volume of the heated air from within the cabinet.

A still further object is to provide in an apparatus of this character a conveying mechanism which will subject the clothes being dried to the action of the heat within the cabinet for the maximum length of time

compared with the dimensions of the cabinet, thus permitting compactness in the structure without sacrificing the capacity of the apparatus.

A still further object is to provide in an apparatus of this character a conveyer mechanism wherein the weight of the clothes will not displace the conveyer in a manner to render it liable to such disarrangement as would render it inoperative.

A still further object is to provide in an apparatus of this character a conveyer mechanism whereby the dried articles will be automatically removed from the conveyer, thus making it necessary to have merely one operative for the apparatus.

A still further object is to provide an apparatus of this character wherein the parts will be so constructed and arranged as to secure high efficiency as to output and uniform drying of the clothes placed therein. And a still further object is to provide an apparatus of this character which will not warp under the moisture and heat, with a resultant opening of seams and leakage.

The invention consists in the novel features of construction and combination of parts hereinafter set forth and described, and more particularly pointed out in the claims hereto appended.

Referring to the drawings:—Figure 1 is a front elevation of a machine embodying my invention; Fig. 2 is a plan view thereof; Fig. 3 is a vertical cross section on the line 3—3 of Fig. 2; Fig. 4 is a longitudinal section; Fig. 5 is a detail view showing a cross section of one corner thereof upon the line 5—5 of Fig. 1; Fig. 6 is a detail view of the conveyer mechanism; Fig. 7 is a detail view of the releasing device of the conveyer mechanism, showing a collar being delivered from the conveyer; and Fig. 8 is a modified form of gripper mechanism adapted for use in connection with my machine.

Like numerals refer to like parts throughout the several views.

In the embodiment of my invention shown in the drawings, 1 indicates a drying cabinet adapted to have a circulation of heated air maintained thereby by means of the blower 2. This cabinet 1 is provided with double walls to prevent the radiation of heat there-

from, and arranged in the bottom thereof is a steam coil 3, adapted to raise the temperature within the cabinet to that desired. To adapt the apparatus to different conditions of use, I also provide in addition to the steam coils 3, gas burners 4, 5, adapted to raise the temperature within the cabinet, thus permitting the machine to be used where steam, or where only gas, is available as a heating medium. In the bottom of the cabinet is a casing or tank 6 adapted to inclose the steam coils 3, said tank being adapted to receive the drippings from the clothes, the drippings being removable from the tank by any suitable means not shown. Extending over the top of this tank is a foraminated drip board 7, having a plurality of openings therein adapted to admit water to the tank and to permit the escape of the air, after being heated by passing about the coils 3, to that portion of the cabinet adapted to accommodate the articles being dried. This board also serves as a distributor for the heated air. The gas burners 4, 5, are arranged in pairs, as shown, upon opposite sides of the cabinet, and above each burner is a foraminated distributor plate 8. Preferably the cabinet 1 is made of sheet metal, and to cheapen the production thereof, give the desired stability thereto, and prevent the escape of the heated air therefrom, I unite the various sections composing same by means of a lap joint of peculiar construction, which I will now describe. This construction is shown more particularly in Fig. 5 of the drawings, in which the inner wall of the cabinet is shown as being comprised of sheet metal sections 9 and the outer wall of sheet metal sections 10. The edges of adjoining sections 10 are turned outwardly, and the ends of these outwardly turned sections turn at right angles as at 12 to form an anchor adapted to be engaged by the lapped edges 9^a of the adjoining sections 9, which pass between a space left between two sections 10 and are turned about and clamped upon the anchors 12 to form a tight joint and at the same time space the two walls 9 and 10 the desired distance apart to form an air chamber between same. The walls of these air chambers are also blocked apart as at 13, to prevent their collapse. To avoid any possibility of the loosening of the lap joint described, I inclose this joint in a housing 14, having a slot therein adapted to have a sliding fit over the lapped edges 9^a. The corners of the cabinet are formed by stepping an edge of the end side plate 9, as shown at 15, the stepped portion being closed by the upset edge 16 of the end section 10. Forming the corner is the angle iron beam 17, about which is formed and crimped the edge of the front plate 18 of the front of the cabinet. The front of the cabinet is formed with door openings at 19, the

portion of the front wall being reinforced upon one side of the door openings by the angle beam 20, about which the front sheet 18 is crimped, a recess 21 being formed between the uprights 17 and 20 for the purpose of reinforcing the front of the cabinet and holding these uprights in position. Opposite the upright beam 20 is a vertical U-beam 22 which acts as one jamb for the door 23 and has the edge of the section 18 folded and crimped about same. The construction upon the other side of the door 23 is a mere duplication of that heretofore described, and throughout the cabinet the various sections entering into the side walls are united in the manner described, thus forming a permanent air-tight wall in a manner which will afford the desired air space between the walls to provide the required inert body of air for insulation purposes.

Leading from the outlet of the pump 2 is a pipe 24 having two branches 25 passing into the cabinet 1. These branches extend adjacent to the bottom of the cabinet 1, and terminate in air distributors 26, 27, extending parallel with, and below, the steam coils 3 near opposite sides of the cabinet. The openings in the distributors are presented upwardly, and the distributors themselves are of gradually reduced diameter to vary the capacity thereof so as to equalize the volume of air delivered at different points thereof. Adjacent to the top of the cabinet are two similar air distributors 28 and 29, the outlet openings of which are presented downwardly, thus causing air to be projected in jets toward the center of the cabinet in a manner to cause it to circulate about the articles being dried, and to prevent the accumulation of moist air within the top of the cabinet. Extending from the delivery pipe 24 is a branch 30, of smaller diameter than said pipe 23, which pipe 30 discharges into a vent or draft pipe 31 for conveying the moist air from the cabinet for the purpose of maintaining the desired constant circulation of air within the cabinet. Communicating with the vent pipe 30 are the branches 32, from which depend the rectangular pipes 33, 34, 35, supporting the foraminated duct 36 extending about three sides of the cabinet adjacent to and above the heating means. By this construction, it will be observed, the air within the cabinet is exhausted by a natural draft through the pipe 31, which exhaustion is accelerated by the siphon or injector action from the branch 30 leading from the pump, the outlet of this pipe 30 being connected with the off take pipe 31 directly above the point of junction of the branches 32 and 33 with said last named pipe. The pump or blower 2 therefore has the twofold function of delivering air to the cabinet while at the same time aiding in the exhaustion of air therefrom to assist in

maintaining the desired circulation of air within the cabinet.

Adapted to have movement within the cabinet 1, is a conveyer 37 carrying a plurality of hangers 38 adapted to receive the articles to be dried. This conveyer is adapted to have continuous movement, and one end thereof is exposed exteriorly of said cabinet 1 so as to permit the operator to attach the articles to be dried thereto and to permit said articles after being dried to the desired extent, to be delivered therefrom exteriorly of said cabinet. This conveyer 37 preferably consists of a sprocket chain which will not be subject to excessive contraction and expansion by the heat within the cabinet. The use of a sprocket chain also permits the conveyer to be readily driven and guided. To increase the interval of time during which the articles are subjected to the action of the heated air circulated within the cabinet 1, I provide guiding means for said conveyer which will cause each hanger 38 to travel back and forth in the cabinet a number of times before passing to the delivery point. These guiding means comprise the three sprocket wheels indicated at 39, 40 and 41, which are triangularly arranged in a manner to cause the conveyer to travel over four parallel courses while within the cabinet.

Mounted exteriorly of the front of the cabinet and preferably in alignment with the sprockets 40 and 41, are the sprockets 42 and 43, about which the chain conveyer 37 passes, these sprockets 42 and 43 being spaced away from the front of the cabinet sufficiently to afford the operator sufficient time to adjust the articles to be dried upon the hangers 38, and at the same time permit space for the positioning of a receptacle to receive the articles delivered from the cabinet by means of the conveyer.

To prevent the sagging of the conveyer between the sprockets 41 and 42, 41 and 39, 39 and 40, and 40 and 43, I provide the T-beams 45, 46, 47 and 48, two of which, as 46 and 48 project forwardly of the cabinet to a point adjacent to the sprockets 42 and 43. Extending across the front of the cabinet between the sprockets 42 and 43 is a T-beam 49 adapted to guide the conveyer between said last named sprockets. The beams 45, 46, 47, 48 and 49 form tracks adapted to receive the rollers 50 on a bracket 51 carried by the chain 37, thus preventing the sagging of this chain and insuring its constant mesh with the various sprocket wheels. These various tracks do not extend about that portion of the periphery of the sprocket wheels engaged by the chain, support not being required at such points. The raised edges of these tracks will serve to confine, or prevent the derailment of, the rollers 50.

The front of the cabinet is provided with

two pairs of self closing doors, 52 and 53, one pair of which as 52 opens inwardly, and the other pair of which as 53 opens outwardly. The tracks 48 and 45 project through suitable openings between the doors of the pairs 52 and 53 respectively, these doors also being provided with openings for the chain 37.

The sprockets 40 and 41 are mounted in bearings carried by the slides 54, which slides are acted upon by a weight 55 in a manner to automatically take up any slack in the conveyer which might result in said conveyer riding upon the sprocket teeth and becoming disengaged therefrom.

The chain 37 has pendant therefrom a plurality of hangers 38 each of which is adapted to support an article to be passed through the drying cabinet. The construction of these hangers 38 may vary to adapt them for use with different articles, the form of hanger shown in Figs. 6 and 7 being especially adapted for use in connection with collars and cuffs, and the modification shown in Fig. 8 being especially adapted for use with other articles which must be gripped by the hanger.

To increase the capacity of the machine, the holding means of the hanger are duplicated so as to increase the capacity of each hanger. The construction of both forms of hangers shown in the drawings is identical with the exception of the detailed construction of the holding means thereof. The hangers 38 each comprise a cross head 56 having bifurcated ends. This cross head is supported by the suspension rod 57 from a link of the chain 37, directly below the yoke 51. The cross head 56 extends for a considerable distance and to an equal degree upon each side of the chain 37, the forked ends thereof being adapted to engage with and open either pair of doors 52 or 53. Each arm of the forked ends is provided with an anti-friction roller as 58 to minimize the friction between the cross heads and the doors.

Depending from the longitudinal center of the cross head 56 is a bracket 59, adapted to carry the means for engaging the article to be dried, the lower end of this bracket being offset as shown for the purpose of permitting the use of an over-balanced co-operating member 60 pivoted thereto at 61. With the form of supporting means shown in Figs. 6 and 7, the bracket 59 carries a post 62 adapted to penetrate the button hole of a collar or cuff, the co-operating member 60 having a bifurcated end straddling said post so as to eject or deliver the articles strung upon said post 62 in a manner to be hereinafter described.

Extending upwardly from the member 60 adjacent to the bifurcated end thereof is an arm 63 by means of which the said member

60 may be automatically actuated to remove the articles therefrom. This mechanism is duplicated on opposite sides of the chain 37.

Mounted exteriorly of the cabinet 1, upon 5 the rail 45, and adjacent to the doors 53, is an elongated cam plate 64 adapted to engage the arm 63 and oscillate the member 60 upon its pivots in a manner to cause the bifurcated end thereof to engage the articles upon 10 the post 62 and deliver them therefrom. There are two cam plates 64 adapted to simultaneously engage both arms 63, so that all articles held by each hanger are simultaneously delivered after leaving the cabinet 15 net.

In the modification shown in Fig. 8, the details of construction of the hanger are substantially the same as heretofore described, excepting that instead of using the 20 post 62, the bracket 59 and the holding member 60 are provided with oppositely disposed holding studs 65 adapted to grip an article between them, the actuation of the member 60 in this form of the invention having the 25 same result as heretofore described, and being accomplished in the same manner.

The pivots 61 of the member 60 being offset as shown, the weight of this member will, in the form of the invention shown in 30 Figs. 6 and 7, make the gripping mechanism operative by exposing the end of the post 62, while in the form of the invention shown in Fig. 8 of the drawings, this weight will have the effect of holding these articles in 35 the desired position.

The chain 37 is driven from the sprocket 39 by means of the beveled gear 66 driven from the beveled gear 67 upon the shaft 68. This shaft is driven from the countershaft 40 69 through pulleys 70-71, and belt 72, the blower 2 being also driven from the shaft 67 by pulleys 73-74 and belt 75. The shaft 68 is geared down, while the blower is geared up. The shaft 69 is driven from the motor 45 76 by means of the belt 77 and pulleys 78. By this construction the speed of traverse of the chain 37 and the volume of air circulated within the cabinet 1 may be simultaneously controlled.

50 The operation of the herein described apparatus is substantially as follows: The blower 2 is first set in operation so as to deliver air through the pipes 25 and distributors 26, 27, 28 and 29 to the cabinet 1, at 55 the same time drawing the air through the duct 36 and pipes 33, 34, 35, and therefrom to the vent pipe 31, the by-pass pipe 30 leading from the delivery pipe of the blower setting up sufficient circulation of air within 60 the pipe 31 to insure the withdrawal of air through the pipes 33, 34 and 35. The air passing from the lower distributing pipes 26, 27, passes upwardly about the heating coils 3 or tubes 4 and 5, and is distrib-

uted by the foraminated plates 7 and 8 to 65 all parts of the cabinet 1. At the same time air from the distributing nozzles 28, 29, will be forced downwardly within the cabinet, preventing the accumulation of moist air in the top of the cabinet, and at the same time 70 blowing directly upon the articles carried by the hangers 38 upon the conveyer 37. The tendency of the air currents in the cabinet will be upwardly toward the center, where the hangers 38 are traveling, and downwardly at the edges adjacent to the duct 36. By this means there is a constant change 75 and agitation of the air within the cabinet, and this air is maintained at substantially uniform temperature and substantially dry. 80

By combining both steam coils and gas burners in the same apparatus, I am enabled to adapt the same machine to either steam heating or gas heating, and if desired both of these forms may be used in one and the 85 same machine.

By the construction of cabinet described, I am enabled to make the entire cabinet of metal, air tight throughout, and having an air insulating space or chamber about all 90 portions thereof excepting the front which is intermittently opened and closed. The central door 23 is merely for the purpose of permitting access to the interior of the cabinet. 95

While the apparatus is in operation, it is merely necessary for one operative to place the articles upon the hangers 38. The machine being in operation, it is merely necessary for this operative, when it is desired to use the machine for drying collars and cuffs, to slip the button hole of the collar or cuff over the post 62, while the chain 37 is in motion, this chain immediately carrying the articles into the cabinet 105 1. The brackets 59 being arranged on the longitudinal center of the cross heads 56, these cross heads when they reach the doors 52 bring the rollers 58 into engagement with said doors and automatically open same inwardly to admit a hanger 38 with the articles thereon to the cabinet. The bifurcated ends of the cross head 56 prevent the closing of 110 these doors until after the articles have passed same, but immediately upon the passage of the cross head 56, these doors automatically close until opened by the next hanger 38. The conveyer chain 37 carries the hangers and the articles supported thereby back and forth within the cabinet four 115 times, finally bringing the cross head 56 into engagement with the doors 53 which are automatically opened outwardly in the same manner as the doors 52 to permit the articles to pass from the cabinet 1, these doors also 120 closing automatically after each hanger 38 has passed therethrough. After the hangers 38 pass through the doors 53, the arms 63

thereof upon opposite sides of the cross head 56 simultaneously engage the cam plates 64 which oscillate the member 60 to cause the bifurcated ends thereof to move 5 along the posts 62 and move any collar or cuff thereon along said stud until it is finally delivered therefrom to a suitable receptacle. Immediately upon passing the plate 64, the weight of the member 60 will cause it to 10 automatically assume its normal position where the post 62 is exposed for the reception of further articles to be dried. The conveyer 37 extending through a portion of the cabinet 1 substantially midway between 15 the heating means and the top of the cabinet, and spaced well away from the sides thereof, brings the articles into a zone where the heated air will circulate freely about same, so that each article carried by the 20 hangers 38 will be subjected to the action of this air in circulation by reason of the tortuous course it follows while within the cabinet, and will be thoroughly dried before being delivered in the manner referred 25 to. The tracks 45, 46, 47, 48 and 49 will prevent the sagging of the chain 37 and at the same time will eliminate any tendency of the chain to twist, in fact sustaining practically the entire load of the conveyer 30 and preserving the desired relative position of the operative parts thereof. If it be desired to increase the time during which the articles undergo the drying operation, it is merely necessary to reduce the speed of the 35 motor, which will reduce the speed of traverse of the conveyer mechanism, at the same time reducing the velocities of the air currents within the cabinet in a manner to raise the temperature of the air within the cabinet 40 slightly.

In the modification shown in Fig. 8, the mode of operation is substantially identical with that heretofore described, except that with the action of the member 60 by the cam plate 64, the grippers 65 will be separated in a manner to drop the article held between same.

It is apparent that one operative only is required to run this machine, as the only 50 work the operator must do is to place the articles upon the hangers 38.

A machine constructed in accordance with my invention has great capacity because of the capability of multiplying the number of 55 hangers upon the one conveyer, and the continuity of operation of the device in drying articles carried by successive hangers. The take-up weight 55 and slides 54 will permit any slight sagging which may occur 60 in the conveyer chain 37 under varying loads, and will automatically take up this slack when necessity demands.

It is not my intention to limit the invention to the precise details of construction

shown in the accompanying drawings, it being apparent that such may be varied without departing from the spirit and scope of the invention. 65

Having described my invention, what I claim as new and desire to have protected by Letters Patent, is:—

1. A machine of the character herein described, embodying therein a cabinet, inwardly opening self-closing doors and outwardly opening self-closing doors arranged 75 at one end of said cabinet, means heating air within said cabinet, a blower and pipe connections therefrom leading to the interior of the cabinet for maintaining a circulation of air therein, a conveyer adapted to have 80 movement within said cabinet, and hangers carried by said conveyer adapted to support articles to be dried.

2. A machine of the character herein described embodying therein a cabinet, inwardly opening self-closing doors and outwardly opening self-closing doors arranged 85 at one end of said cabinet, means adapted to heat air within said cabinet, a blower and pipe connections therefrom leading to the 90 interior of the cabinet for maintaining a circulation of air therein, a conveyer having the receiving and delivery points thereof exposed exteriorly of said cabinet and adapted to move through said cabinet, and hangers 95 carried by said conveyer adapted to support articles to be dried.

3. A machine of the character herein described embodying therein a cabinet, inwardly opening self-closing doors and outwardly opening self-closing doors arranged 100 at one end of said cabinet, means heating air within said cabinet, a blower and pipe connections therefrom leading to the interior of the cabinet for maintaining a circulation 105 of air therein, a conveyer adapted to have movement within said cabinet, hangers carried by said conveyer adapted to support articles to be dried, and means imparting continuous traverse to said conveyer. 110

4. A machine of the character herein described embodying therein a cabinet, inwardly opening self-closing doors and outwardly opening self-closing doors arranged 115 at one end of said cabinet, means adapted to heat air within said cabinet, a blower and pipe connections therefrom leading to the interior of the cabinet for maintaining a circulation of air therein, a conveyer having the receiving and delivery points thereof exposed exteriorly of said cabinet and adapted to move through said cabinet, hangers carried by said conveyer adapted to support articles to be dried, and means imparting continuous traverse to said conveyer. 120

5. A machine of the character herein described embodying therein a cabinet, inwardly opening self-closing doors and out-

wardly opening self-closing doors arranged at one end of said cabinet, means heating air within said cabinet, a blower and pipe connections therefrom leading to the interior of the cabinet for maintaining a circulation of air therein, a conveyer adapted to have movement within said cabinet, guides for said conveyer divergently arranged within said cabinet whereby the conveyer is caused to traverse a tortuous course, and hangers carried by said conveyer adapted to support articles to be dried.

6. A machine of the character herein described embodying therein a cabinet, inwardly opening self-closing doors and outwardly opening self-closing doors arranged at one end of said cabinet, means heating air within said cabinet, a blower and pipe connections therefrom leading to the interior of the cabinet for maintaining a circulation of air therein, a conveyer adapted to have movement within said cabinet, guides for said conveyer divergently arranged within said cabinet whereby said conveyer is caused to traverse a tortuous course, tracks extending from adjacent to one guide to the other, rolling supports carried by said conveyer adapted to engage said tracks, and hangers carried by said conveyer adapted to support articles to be dried.

7. A machine of the character herein described embodying therein a cabinet, inwardly opening self-closing doors and outwardly opening self-closing doors arranged at one end of said cabinet, means heating air within said cabinet, a blower and pipe connections therefrom leading to the interior of the cabinet for maintaining a circulation of air therein, a conveyer adapted to have movement within said cabinet, guides for said conveyer divergently arranged within said cabinet whereby said conveyer is caused to traverse a tortuous course, tracks extending from adjacent to one guide to the other, the first and last of said tracks projecting exteriorly of said cabinet, guides adjacent to the ends of said tracks projecting exteriorly of said cabinet, a track extending from adjacent to one of said last named guides to the other, rolling supports carried by said conveyer adapted to engage said tracks, and hangers carried by said conveyer adapted to support articles to be dried.

8. A machine of the character herein described embodying therein a cabinet, inwardly opening self-closing doors and outwardly opening self-closing doors arranged at one end of said cabinet, means heating air within said cabinet, a blower and pipe connections therefrom leading to the interior of the cabinet for maintaining a circulation of air therein, a conveyer adapted to have movement within said cabinet, guides for said conveyer divergently arranged within said cabinet whereby said conveyer is

caused to traverse a tortuous course, inverted T-tracks extending from adjacent to one guide to the other, a plurality of brackets carried by said conveyer, rollers carried by said brackets and adapted to be seated within the flange of said tracks, and hangers carried by said conveyer adapted to support articles to be dried.

9. A machine of the character herein described embodying therein a cabinet, inwardly opening self-closing doors and outwardly opening self-closing doors arranged at one end of said cabinet, means heating air within said cabinet, a blower and pipe connections therefrom leading to the interior of the cabinet for maintaining a circulation of air therein, a conveyer adapted to have movement within said cabinet, guides for said conveyer divergently arranged within said cabinet whereby said conveyer is caused to traverse a tortuous course, inverted T-tracks extending from adjacent to one guide to the other, the first and last of said tracks projecting exteriorly of said cabinet, guides adjacent to the ends of said tracks projecting exteriorly of said cabinet, an inverted T-track extending from adjacent to one of said last named guides to the other, a plurality of brackets carried by said conveyer, rollers carried by said brackets and adapted to be seated within the flange of said tracks, and hangers carried by said conveyer adapted to support articles to be dried.

10. A machine of the character herein described embodying therein a cabinet, inwardly opening self-closing doors and outwardly opening self-closing doors arranged at one end of said cabinet, means heating air within said cabinet, a blower and pipe connections therefrom leading to the interior of the cabinet for maintaining a circulation of air therein, a conveyer adapted to have movement within said cabinet, guides for said conveyer divergently arranged within said cabinet whereby said conveyer is caused to traverse a tortuous course, inverted T-tracks extending from adjacent to one guide to the other, the first and last of said tracks projecting exteriorly of said cabinet, guides adjacent to the ends of said tracks projecting exteriorly of said cabinet, an inverted T-track extending from adjacent to one of said last named guides to the other, a plurality of brackets carried by said conveyer, rollers carried by said brackets and adapted to be seated within the flange of said tracks, automatic take-up means acting upon the guides within said cabinet whereby slack in said conveyer will be automatically taken up, and hangers carried by said conveyer adapted to support articles to be dried.

11. A machine of the character herein described, embodying therein a cabinet, in-

wardly opening self-closing doors and outwardly opening self-closing doors arranged at one end of said cabinet, means maintaining a circulation of air within said cabinet, 5 said means including a blower and pipe connections leading therefrom to the interior of the cabinet, a conveyer, adapted to have movement within said cabinet, and hangers carried by said conveyer adapted to support articles to be dried.

10 12. A machine of the character herein described, embodying therein a cabinet, inwardly opening self-closing doors and outwardly opening self-closing doors arranged 15 at one end of said cabinet, means maintaining a circulation of air within said cabinet, said means including a blower and pipe connections leading therefrom to the interior of the cabinet, a conveyer having the receiving and delivery ends thereof exposed exteriorly of said cabinet and adapted to move through said cabinet, and hangers carried by said conveyer adapted to support articles to be dried.

20 13. A machine of the character herein described, embodying therein a cabinet, inwardly opening self-closing doors and outwardly opening self-closing doors arranged at one end of said cabinet, means maintaining a circulation of air within said cabinet, 25 said means including a blower and pipe connections leading therefrom to the interior of the cabinet, means adapted to heat the air within said cabinet, a conveyer adapted to have movement within said cabinet, and 30 hangers carried by said conveyer adapted to support articles to be dried.

35 14. A machine of the character herein described, embodying therein a cabinet, inwardly opening self-closing doors and outwardly opening self-closing doors arranged 40 at one end of said cabinet, means maintaining a circulation of air within said cabinet, said means including a blower and pipe 45 connections leading therefrom to the interior of the cabinet, means adapted to heat the air within said cabinet, a conveyer having the receiving and delivery ends thereof exposed exteriorly of said cabinet and adapted to move through said cabinet, and 50 hangers carried by said conveyer adapted to support articles to be dried.

55 15. A machine of the character herein described embodying therein a cabinet, means circulating air therein comprising a blower, pipes extending therefrom to adjacent the bottom of said cabinet, air distributers leading from said pipes and delivering air to different portions of said cabinet, and an 60 air off-take, and means adapted to support articles to be dried within said cabinet.

65 16. A machine of the character herein described embodying therein a cabinet, means circulating air therein comprising a blower, pipes extending therefrom to adjacent the

bottom of said cabinet, air distributers leading from said pipes adjacent to the top and the bottom of said cabinet, and delivering air to different portions of said cabinet, the outlet openings of the upper distributers being directed downwardly, and those of the lower distributers being directed upwardly, and an air off-take, intermediate said distributers, and means intermediate said distributers adapted to support articles to be dried within said cabinet.

70 17. A machine of the character herein described embodying therein a cabinet, means circulating air therein comprising a blower, pipes extending therefrom to adjacent the bottom of said cabinet, air distributers leading from said pipes adjacent to the top and the bottom of said cabinet, and delivering air to different portions of said cabinet, the outlet openings of the upper distributers being directed downwardly, and those of the lower distributers being directed upwardly, and an air off-take intermediate said distributers comprising a duct having inlet openings extending about said cabinet, a plurality of pipes leading from said duct, and a vent pipe communicating with said last named pipes, and means intermediate said distributers adapted to support articles to be dried.

75 18. A machine of the character herein described, embodying therein a cabinet, means circulating air therein comprising a blower, pipes extending therefrom to adjacent the bottom of said cabinet, air distributers leading from said pipes adjacent to the top and the bottom of said cabinet, and delivering air to different portions of said cabinet, the outlet openings of the upper distributers being directed downwardly, and those of the lower distributers being directed upwardly, and an air off-take intermediate said distributers comprising a duct having inlet openings extending about said cabinet, a plurality of pipes leading from said duct, a vent pipe communicating with said last named pipes, and a by-pass pipe leading from said blower off-take and discharging into said vent pipe, and means intermediate said distributers adapted to support articles to be dried.

80 19. A machine of the character herein described embodying therein a cabinet, means circulating air therein comprising a blower, pipes extending therefrom to adjacent the bottom of said cabinet, air distributers leading from said pipes adjacent to the top and the bottom of said cabinet, and delivering air to different portions of said cabinet, the outlet openings of the upper distributers being directed downwardly, and those of the lower distributers being directed upwardly, and an air off-take intermediate said distributers, comprising a duct having inlet openings extending about said cabinet, a plurality of pipes leading from said duct, a vent pipe communicating with said last

- named pipes, and a by-pass pipe leading from said blower off-take and discharging into said vent pipe, a conveyer mounted within said cabinet intermediate said distributers, and above said duct, and hangers carried by said conveyer and adapted to support articles to be dried.
20. A machine of the character herein described embodying therein a cabinet, means circulating air therein comprising a blower, pipes extending therefrom to adjacent the bottom of said cabinet, air distributers leading from said pipes and delivering air to different portions of said cabinet, and an air off-take, steam heating coils arranged above said distributers and below said off-take, and means adapted to support articles to be dried within said cabinet.
21. A machine of the character herein described, embodying therein a cabinet, means circulating air therein comprising a blower, pipes extending therefrom to adjacent the bottom of said cabinet, air distributers leading from said pipes and delivering air to different portions of said cabinet, and an air off-take, steam heating coils arranged above said distributers and below said off-take, a foraminated plate above said coils, and means adapted to support articles to be dried within said cabinet.
22. A machine of the character herein described embodying therein a cabinet, means circulating air therein comprising a blower, pipes extending therefrom to adjacent the bottom of said cabinet, air distributers leading from said pipes and delivering air to different portions of said cabinet, and an air off-take, steam heating coils and gas burners arranged above said distributers and below said off-take, and means adapted to support articles to be dried within said cabinet.
23. A machine of the character herein described, embodying therein a cabinet, means circulating air therein comprising a blower, pipes extending therefrom to adjacent the bottom of said cabinet, air distributers leading from said pipes and delivering air to different portions of said cabinet, and an air off-take, steam heating coils and gas burners arranged above said distributers and below said off-take, foraminated plates above said coils and said burners, and means adapted to support articles to be dried within said cabinet.
24. A machine of the character herein described embodying therein a cabinet, means circulating air therein comprising a blower, pipes extending therefrom to adjacent the bottom of said cabinet, air distributers leading from said pipes and delivering air to different portions of said cabinet, and an air off-take, steam heating coils arranged above said distributers and below said off-take, a tank below said coils, a foraminated cover for said tank above said coils, and means adapted to support articles to be dried within said cabinet.
25. A machine of the character herein described embodying therein a cabinet, inwardly opening self-closing doors and outwardly opening self-closing door arranged at one end of said cabinet, means adapted to heat air within said cabinet, a blower and pipe connections therefrom leading to the interior of the cabinet for maintaining a circulation of air therein, a conveyer having the receiving and delivery points thereof exposed exteriorly of said cabinet and adapted to move through said cabinet, hangers carried by said conveyer adapted to support articles to be dried, and automatically operative means adjacent said delivery point whereby the dried articles are removed from said hangers.
26. A machine of the character herein described embodying therein a cabinet, inwardly opening self-closing doors and outwardly opening self-closing doors arranged at one end of said cabinet, means adapted to heat air within said cabinet, a blower and pipe connections therefrom leading to the interior of the cabinet for maintaining a circulation of air therein, a conveyer having the receiving and delivery points thereof exposed exteriorly of said cabinet and adapted to move through said cabinet, a plurality of hangers carried by said conveyer, each comprising means adapted to engage the article to be dried, and an oscillatory member adapted to disengage an article from said means, and means adjacent the delivery point of said conveyer, adapted to actuate said oscillatory member.
27. A machine of the character herein described embodying therein a cabinet, inwardly opening self-closing doors and outwardly opening self-closing doors arranged at one end of said cabinet, means adapted to heat air within said cabinet, a blower and pipe connections therefrom leading to the interior of the cabinet for maintaining a circulation of air therein, a conveyer having the receiving and delivery points thereof exposed exteriorly of said cabinet and adapted to move through said cabinet, a plurality of hangers carried by said conveyer, each hanger comprising a bracket, a post carried thereby, and a bifurcated oscillatory member mounted upon said bracket and straddling said post, and means adjacent the delivery point of said conveyer adapted to actuate said oscillatory member to remove articles from said post.
28. A machine of the character herein described embodying therein a cabinet, inwardly opening self-closing doors and outwardly opening self-closing doors arranged at one end of said cabinet, means adapted to heat air within said cabinet, a blower and pipe connections therefrom leading to the

- interior of the cabinet for maintaining a circulation of air therein, a conveyer having the receiving and delivery points thereof exposed exteriorly of said cabinet and adapted 5 to move through said cabinet, a plurality of hangers carried by said conveyer, each hanger comprising a bracket, a post carried thereby, and a bifurcated oscillatory member mounted upon said bracket and straddling said post, and a cam plate adjacent the delivery point of said conveyer adapted to actuate said oscillatory member to remove 10 articles from said post.
29. A machine of the character herein described embodying therein a cabinet, means adapted to heat air within said cabinet, a blower and pipe connections therefrom leading to the interior of the cabinet for maintaining a circulation of air therein, 15 a conveyer having the receiving and delivery points thereof exposed exteriorly of said cabinet and adapted to move through said cabinet, self-closing, inwardly opening doors in said cabinet adjacent said receiving point 20 of said conveyer, self-closing, outwardly opening doors in said cabinet adjacent the delivery point of said conveyer, a plurality 25
- of hangers carried by said conveyer and adapted to support articles to be dried, and means carried by said hangers respectively, 30 adapted to engage and open said doors.
30. A machine of the character herein described embodying therein a cabinet, means adapted to heat air within said cabinet, a conveyer having the receiving and delivery points thereof exposed exteriorly of said cabinet and adapted to move through said cabinet, self-closing, inwardly opening doors in said cabinet adjacent said receiving point of said conveyer, self-closing, 35 outwardly opening doors in said cabinet adjacent the delivery point of said conveyer, a plurality of hangers carried by said conveyer and adapted to support articles to be dried, and a cross head carried by said conveyer adjacent each hanger, having rollers in advance and to the rear of the hanger 40 adapted to engage and open said doors.

In testimony whereof I have affixed my signature in presence of two witnesses.

LOUIS JUDELSON.
